[57] CLAIM

The ornamental design for a winter/summer ski, as shown and described.

DESCRIPTION

FIG. 1 is a front elevational view of a winter/summer ski showing my new design, in the winter ski mode embodiment;

FIG. 2 is a rear elevational view of FIG. 1;

FIG. 3 is a left side elevational view of FIG. 1;

FIG. 4 is a right side elevational view of FIG. 1;

FIG. 5 is a top plan view of FIG. 1;

FIG. 6 is a bottom plan view of FIG. 1;

FIG. 7 is a front elevational view of a winter/summer ski, in the summer ski mode embodiment;

FIG. 8 is a rear elevational view of FIG. 7;

FIG. 9 is a left side elevational view of FIG. 7;

FIG. 10 is a right side elevational view of FIG. 7;

FIG. 11 is a top plan view of FIG. 7;

FIG. 12 is a bottom plan view of FIG. 7;

FIG. 13 is a top perspective view of FIG. 1;

FIG. 14 is a bottom perspective view of FIG. 1; and

FIG. 15 is a bottom perspective view of FIG. 7.
